CORE TAKER FOR ROTARY DRILLS

Ancil Brooks Conklin, Galveston, Tex.

Application December 28, 1937, Serial No. 182,122

15 Claims. (Cl. 255—72)

This invention relates to rotary well drilling mechanism using a tubular drill and drill pipe and particularly to means for drilling and taking cores as samples of the stratum in which the drill is working and by means of a wire line. In wire line retractile core drills known to me, this core barrel is rotated with the drill, thus causing great friction on the core and burning and crystallizing the core. An object of my invention is, therefore, to provide core taking means removable or retractile by a wire line which includes an idling core barrel, that is, one which will not rotate with the drill and, therefore, not rotate around the core being cut, but will permit the core to slip up into the barrel with a minimum of friction and thus provide means whereby to cut long uncontaminated cores which will reveal the true condition of the formation being drilled.

A further object is to so construct the core barrel and allied parts that the core will reveal the true condition of the formation being drilled and provide means whereby the polarity of the core can be immediately determined upon the arrival of the core on the derrick floor.

A still further object is to provide a divided core barrel which greatly simplifies the removal of the core, the barrel being so constructed that when it is withdrawn from the drill pipe it may be separated into two longitudinal halves permitting the removal of the core without any destruction or injury to the core itself and doing away with the necessity of pounding the core barrel on the derrick floor in order to shake the core out and preventing the core from being otherwise deformed or injured in order to secure its removal from the barrel.

A still further object is to provide a core catcher mounted upon the core drill, the core catcher or catchers being so formed that they will be operative either in soft or hard formations and further being so constructed as to greatly reduce the number of parts.

A further object in this connection is to provide core catchers which will nearly completely close the bore of the core barrel and which will cut the core off adjacent the bottom of the main drill so that the operator will know just what the drill has penetrated.

Still another object is to provide a water channel or duct in each blade of the main drilling bit so arranged and constructed as to jet the drilled mud out through the rear side of the blade and against the cutting edge of the succeeding blade, thus keeping the blades at all times free from cut-

tings, lengthening the life of the bit and preventing sticky formation from balling up on it.

Other more detailed objects will appear in the course of the following description.

My invention is illustrated in the accompanying drawings wherein:

Fig. 1 is a vertical section of a rotary well drilling and core taking mechanism constructed in accordance with my invention.

Fig. 2 is an elevation of the core bit and barrel, 10 the clamps being in section.

Fig. 3 is an elevation partly in section of the collar whereby rotary motion is communicated from the drilling bit to the core bit.

Fig. 4 is an underside plan view of the collar 15 shown in Fig. 3.

Fig. 5 is a section on the line 5—5 of Fig. 1.

Fig. 6 is a section on the line 6—6 of Fig. 1.

Fig. 7 is a side elevation of one of the core catchers.

Fig. 8 is a front elevation thereof.

Fig. 9 is a section on the line 9—9 of Fig. 8.

Fig. 10 is a section on the line 10—10 of Fig. 1.

Fig. 11 is a fragmentary sectional view through one of the blades of the main drill bit showing 25 the spraying nozzle thereon.

Referring now particularly to Figs. 1 and 2, 10 designates generally the drilling bit. This drilling bit is of the box type having four blades 11, as shown in Fig. 10, and in each of these blades 30 there is a vertical water duct 12. Two of these water ducts are shown in Fig. 1 and each water duct at its upper end is inwardly and upwardly inclined, as at 13, and opens upon the inner face of the annular bit 10. Each water duct 12 below 35 the root of the blade 11 is extended rearward relative to the direction of rotation of the bit and opens upon the rear face of the blade. Within this rearwardly extended portion 14 there is disposed a nozzle 15 having a plurality of apertures 40 by means of which the liquid is directed to two different points along the cutting edge of the rear blade. (See Fig. 11.) While in Fig. 1, I have illustrated a four-blade, drag-type drilling bit, it is intended that there may be a hard-for- 45 mation roller type bit which will be interchangeable with the bit shown in Fig. 10. I have not illustrated this roller type of bit as this type of bit is well known and forms no part of my invention in itself. The bit 10 at its upper end is in- 50 teriorly screw-threaded, as at 16, and coacting with this outwardly flared screw-threaded portion is the tubular joint or section 17 which is approximately 10 ft. or more in length and which at its upper end is tapered and exteriorly screw- 55

threaded at 18 for engagement with a short upper substitute (not shown) which connects with the drill pipe. Preferably the interior face of this pipe section 17 is formed with a plurality of longitudinally extending grooves or channels 19 in order to permit of an increased quantity of liquid which is being pumped to the drilling bit by increasing the unobstructed area inside of this drill collar or pipe section 17. The utility of these grooves will appear more fully hereinafter. It will be seen that the drill collar 17 has a slightly tapered bore which will permit the passage of the core barrel assembly and that the interior diameter of the drill 10 is slightly greater than that of the drill collar but that at its lower end the drill 10 has an inwardly extending shoulder 20. Just below the upper ends of the ducts 13, the interior face of the drill 10 is screw-threaded at 21, and disposed within the lower portion of the drill 10 and resting upon the shoulder 20 is a sleeve or bushing 22 which at its upper end is screw-threaded for engagement with the screw-threads 21. A clearance groove 23 is formed in the inner face of the drill 10 just below the screw-threads 21. The bushing 22 at its lower end is formed at opposite points with inwardly projecting thickened portions or lugs 24 and 25, each of these lugs or thickened portions being undercut, as at 26. The spaces 27 and 28 between these lugs are of different widths, as shown clearly in Fig. 4, the space 27 being much wider than the space 28. These lugs 24 and 25 constitute bayonet joints for a purpose to be later stated. It may be remarked also that the threads 21 are left-hand threads.

Adapted to operate through the drill collar 17 and the drill 10 and through the tubular sections of the drilling string is the core barrel and core cutting mechanism shown particularly in Fig. 2 as removed from the drill.

This comprises the core cutter 29 which at its lower end is provided with the usual teeth 30. These teeth on this core cutter head 29 are slightly turned in at the cutting tip so that they will cut a core just a little smaller than the uniform interior diameter of the core cutter head which extends up to a point approximately even with the cutting edge of the blades of bit 10. This cutter head 29 has an exterior diameter 50 slightly less than the interior diameter of the bit 10 below the shoulder 20, so that it may move easily through the central aperture in the lower end of the bit 10. The upper end of the cutter 29 is exteriorly screw-threaded at 30. Having screw-threaded engagement with threads 30 is a collar 31 formed, as shown in Fig. 2, with oppositely disposed downwardly extending lugs 32 and 34. Each of these lugs has an angular extension 33 at its lower end. These parts 32 and 34 60 constitute, with the lugs 24 and 25, a bayonet joint connection. As illustrated in Fig. 2 in dotted lines, the opposed lug 34 is much narrower than the lug 32. This lug 34 fits within the recess 28 of the bushing 22 while the lug 32 fits 65 within the recess 27 of this bushing. The necessity of providing lugs of different widths and making the spaces 27 and 28 of different widths will appear more fully hereinafter.

As illustrated in Fig. 1, the upper end of the collar 31 is formed with an annular channel 35. From Fig. 1, it will be seen that the core cutting head 29 has a uniform interior diameter up to a point approximately even with the cutting edge of the blades of the drill bit 10 and that from 75 there on, the interior of core cutter 29 grad-

ually increases in diameter slightly and the internal diameter of the collar 31 is equal to the interior diameter of the upper end of the core cutting head 29.

Disposed above the collar 31 and extending upward within the pipe section 17 and having a length of approximately 10 ft. is the core barrel designated generally 36. This core barrel is formed in two interchangeable halves, the line of separation between the two halves of the core barrel being designated 37 in Fig. 1. Inasmuch as both halves are alike and inasmuch as both halves when placed together form a cylindrical core barrel, the core barrel will be described as a unit. This core barrel is formed at least 10 two, and preferably three, points along its length with annular grooves 38. One of these grooves is shown as being disposed adjacent the lower end of the core barrel, the other groove adjacent the upper end of the core barrel. These grooves are 20 for the reception of split rings 39 shown in Fig. 5, which rings act to hold the two sections of the core barrel in closed relation. The split rings are resilient so that they may be expanded and taken off the core barrel in order to permit the 25 sections of the core barrel to be opened one from the other when the core barrel is taken out of the hole.

The lower end of the core barrel has an external diameter less than and fitting loosely within 30 the internal diameter of the bushing 22. At its lower end the core barrel is recessed so as to provide an inwardly extending annular flange 40 which extends into the groove 35 of collar 31. The recess extends upward above the upper end 35 of the collar 31 to provide for the reception of opposed raceways 41, there being bearing balls disposed in these raceways. Thus the collar 31 has fixed engagement with the core cutter 29 (that is, it rotates with the cutter head 29) but 40 has rotative engagement with the core barrel 36. The core barrel adjacent its upper end is annularly recessed at 42 and the upper extremity of the core barrel is upwardly and inwardly tapered at 43. Set within the upper end of the core barrel 45 is the cylindrical valve cage 44 having a flange 45 at its lower end which fits within the annular recess 42. The exterior diameter of this cage is equal to the interior diameter of the upper end of the core barrel and the lower end of the cage 50 is formed with a seat 46 for a ball valve 47. The upper end of the cage is closed by a plug 48 having a plurality of longitudinally extending apertures 49 in it and having a central interiorly screw-threaded hub into which the spear head 55 and pull bar 50 is screwed, this pull bar having at its upper end the usual tapering spear head wherewith the locking dogs of an overshot may be engaged to permit the core barrel and allied parts to be drawn to the surface. The exterior 60 diameter of the core barrel is reduced between its upper end portion and the middle portion, as at 51, and between this middle portion and the lower end portion of the core barrel there is a second reduction 52, these reduced portions being 65 for the purpose of permitting the free passage of liquid.

It will be noted from Fig. 1, that the grooves 19 are disposed opposite the relatively large diameter of the upper end of the core barrel and 70 these are also for the purpose of permitting the free flow of liquid when the core barrel is properly in place. The upper end of the core barrel has an external diameter nearly that of the internal diameter of the pipe section 17 both above 75

the weight of the core barrel assembly from the bushing 22, and rotated approximately half a turn in a counterclockwise direction. This will cause the collars 22 and 31 to become unlocked. 5 The overshot is then run on the wire line and the core barrel assembly withdrawn. When the assembly reaches the derrick floor, the overshot is released from the spear head 50 and the barrel 36 laid in a horizontal position. The clamps 38 10 are then removed and one-half of the idling inner barrel is removed from the core. This core may then be removed from the other half of the core barrel, if desired; if another core is desired, the assembly is made up as before and dropped into 15 the well.

It is to be understood that where drilling is being done without coring, there is a center bit which is dropped into place within the drill 10 and takes the place of the core barrel assembly. 20 This center bit fits into the main bit 10 in exactly the same manner as the core barrel does but instead of cutting a core, it serves as a continuation of the cutting edges of the main drilling bit 10, closing the hole in the lower end of the bit. 25 The center bit may be provided with a spear head so as to be retrieved in the same manner as the core barrel.

The advantages of this construction are many. 30 The idling inner core barrel 36 which has swiveled engagement with the core cutter 29 eliminates the burning effect caused by the core barrel revolving around the core and prevents the core from becoming crystallized. If the core is crystallized, this condition by no means represents a 35 true sample of the formation from which the core was taken. In my construction, the only movement of the core barrel is to slip gradually over the core as the drilling progresses and the main drill bit 10 and the core cutter 29 move downward. 40 With my arrangement, due to the position of the teeth in the core cutter, the gradual increase in diameter in the upper portion of the core cutter 29 and the downward taper at the lower end of the core cutter with the idling 45 inner barrel, it is possible to cut long cores. The core being uninjured by burning or crystallization will reveal the true condition of the formation being drilled and the polarity of which can immediately be determined.

50 The divided core barrel 36 greatly simplifies the removal of the core. It eliminates the use of any sort of core removing device such as screws, jacks, rams or hydraulic pumps. It does away with the necessity of pounding the core barrel 55 on the derrick floor in an attempt to get the core out and it does away with the necessity of washing out the core with water.

Since the core cutter 29 and the collar 31 will interlock with the drilling bit 10 in only one 60 position of the collar 31 with relation to the bushing 22, it is possible, by noting the position of the bushing 22 in relation to the bit and by orienting the drill pipe in the well, to determine the polarity of the core immediately on its arrival on the derrick floor.

It is common practice to "orient" a drill pipe, 65 that is, to keep a check on the position of the first joint of the drill pipe in order to control the direction of drilling to thus bring back or keep the drilling bit under the lease or control the 70 direction of drilling where directional relief wells are being drilled. Inasmuch as it is possible to orient or keep a check on the drill bit and since my core barrel will fit the drill bit in only one 75 position, the operator will know by observing

a mark on the last joint of the drill pipe the 5 exact position of the core barrel at the time when the drill pipe is raised to cause the core catchers to shear off the core. After the core is sheared off, the lowest unbroken section of core in the 10 barrel will not change its position in relation to the core catcher and core cutter head, that is, the core drill, and so by noting the position of the two locking extensions on the collar 31 which differ 15 greatly in size, the operator will know, when the assembly is reeled to the surface, which side of the 20 core is the north side. By this means, the "polarity" of the core, that is, which part of the core 25 was pointing toward the north before it was removed from the earth, may be readily determined. 15

At the present time, it is necessary to ship the core to a distant laboratory in order to obtain 20 this information. By providing means whereby the polarity of the core may be known, it is possible to determine the direction and approximate amount of "dip" or "strike" in the sub-surface formation in which the drilling is being done, and this information is particularly valuable in the case of "wildcat" drilling or where the 25 boundary of a newly discovered field has not been established.

The specially formed water-course in each 30 blade of the drilling bit 10 serves to jet the drilling mud out through the rear face of the blade and against the cutting edge of the following 35 blade. This keeps the blades at all times free of cuttings, lengthening the life of the bit and preventing sticky formation from balling the bit up.

In rotary drilling, the mud, which is pumped 35 from the slush pit up through the swivel joint and down through the drill pipe to the drilling bit is caused to whirl by the rotation of the drill pipe. This motion is clockwise and it is in order to keep the mud from causing the idling inner barrel to 40 revolve that the spiral fins 53 are provided, which are arranged so that the mud in its downward movement strikes the fins and this offsets the fluid friction between the mud and the exterior 45 surface of the core barrel assembly, making it possible for the core barrel assembly to remain in a stationary position.

Particular attention is called to the fact that the core catchers 54 are combination hard and soft core catchers; that is, they are so hard, sharp 50 and rigid that they will shear off the hardest cores and when they have moved down to a position across the barrel and at right angles thereto, they practically completely close the core barrel 55 so that the very softest and most unconsolidated cores will not sift or leak through between or around the catchers. In other core-taking structures known to me, the hard formation catchers by no manner of means close the barrel but would permit the escape of soft cores, while the 60 soft formation catchers are in the form of easily flexed springs which move aside to permit the inward movement of the core and then "wad up" in the core to prevent the core from dropping out. Such springs as these could not possibly cut into 65 a hard core.

What is claimed is:—

1. A core taking assembly for rotary drills, including a core cutting bit, means constructed and arranged for detachably connecting the core cutting bit with the rotary drill for unitary rotary movement in one direction but disconnecting the core cutting bit from the drill upon a rotary movement of the drill in the other direction to thereby permit the lifting of the core taking as- 75

and below the grooves 19. On the reduced portion 51 and disposed upon the exterior of the core barrel are the two spiral fins 53 which extend spirally through 180° in the same direction to 5 each other, there being a fin on each section of the core barrel. These fins serve to offset the twist imparted to the core barrel by the whirling column of mud which is being pumped down through the drill pipe and through the section 17 10 and out through the ducts 12.

10 Mounted within the core cutter 29 approximately opposite the extreme lower end of the main drill 10 are a plurality of core catchers which in a sense act as pawls in that they are so 15 mounted that they permit the upward movement of the core within the drill but as soon as the drill is pulled upward and the tendency of the core is to move downward with relation thereto, the core catchers will turn upon their pivots and 20 cut through the core and hold the upper portion of the core from any downward movement. These core catchers are shown in detail in Figs. 6 to 9.

As illustrated in Fig. 8, each core catcher 54 is approximately triangular in shape except that 25 the lower edge 55 is curved on the same radius as the radius of the inside diameter of the core cutter, so that when they are swung downward to a horizontal position, this curved rear edge will fit closely against the inner face of the core cutter. 30 The inside surface of each catcher 54 is also curved, as shown in Fig. 9, at 56, to the same radius as that of the inside diameter of the part 29 so that while in drilling position, except for the sharp inwardly extending points 57, each 35 core catcher will fit flush into the wall of the core cutter, allowing the core to pass freely. The sharp chisel point 57 which forms the upper tip of the catcher does not recede into the wall but projects slightly inward and upward, as shown in 40 Fig. 1, so that when the main bit 10 is raised slightly, the points of the catchers will dig into the core. Each core catcher is so shaped that once it is started inward upon a lifting movement applied to the main bit 10, the core catcher 45 will swing readily toward the center of the core cutter, shearing off the core and closing the bore of the core cutter. The core catchers can only drop to a horizontal position due to the fact that the extreme right and left-hand portions of the 50 curved back 55 will come in contact with the wall of core cutter 29 when the catchers have dropped to a horizontal position. Each core catcher is formed with a reinforcing rib 58 at its back and this rib is extended downward to form a 55 lug 59 having an elongated or elliptical passage 60 through it and through this passage passes the pivot pin 61 shown in dotted lines in Fig. 6. The passageways for these pins 61 are formed in the wall of the core bit 29, opening upon the 60 outer face of the core bit so as to permit the insertion and withdrawal of these pivot pins. By forming the opening 60 elliptical, each core catcher will be free to move up or down slightly so that when the device is raised to close the core 65 catchers, the downward pressure of the core on the sharp tip of the core catcher will not be supported on the pivot pin 61 but on the end of the core catcher and the seat within which the core catcher rests, each seat being formed by a recess 70 in the wall of cutter head 29, as shown best in Figs. 1 and 6.

Attention is again called to the fact that the spaces 21 and 28 between the lugs 24 and 25 in bushing 22 are considerably different in width and 75 that the two extensions or lugs 32 and 34 differ

in width and each can only fit in the corresponding space 27 or 28. This is a very important feature of my invention as this prevents the core barrel from being inserted fully into the drill 5 10 except in one position of the parts. It will be noted that the interior diameter of the collar 31 at the extensions 32 and 34 is slightly greater than the external diameter of the threads 30 on the upper end of the core cutter 29, so that these extensions 32 and 34 will slip down over the core 10 cutter head 29 when the two parts are screwed together.

In assembling the parts, the core catchers 54 are put in place in the wall of the core cutter and fastened by the small pins 61. The collar 31 is 15 then screwed upon the upper end of the core cutter. The shank of the spear head 50 is then 20 screwed into place after the ball 47 has been put in place, of course. The sleeve 22 is screwed into the upper end of the drill 10 and its position is noted 25 if the implement is to be oriented in the drill hole. The raceways 41 containing the bearing balls are placed on top of the collar 31 and the two sections of the core barrel are then put in place so as to engage the flange 45 and engage 30 the recess 35 of collar 31 and are clamped in place by the clamps 39. The assembly is then ready to be dropped down through the drill pipe. These parts, as assembled in the manner shown in Fig. 2, constitute the core barrel assembly. 35

The operation of this structure is as follows:

After the core barrel assembly, as shown in Fig. 2, has been dropped into the drill pipe and has reached the drilling bit 10, a Kelly joint is 40 screwed into the drill pipe and the mud pump 35 started. If circulation is possible, it will be because the collar 22 and the collar 31 are properly matched and are in position such that the bayonet joint formed by these parts will become locked on rotation. Assuming that the bayonet joint of 45 the bushing 22 has been properly matched with the bayonet joint of the collar 31, then drilling is continued until the desired length of core has 50 been cut. If the bayonet joints of the bushing 22 and collar 31 are not matched properly, circulation cannot be started because the core barrel 55 will not have reached its lowest point in the bit 10 and the drill collar 17, consequently the lower shoulder on the core barrel 36 will not have passed out through the lower end of the drill collar 17 50 which tapers inwardly. Thus it will be known that the core barrel assembly has not reached its lowest point in the drill 10 and in the pipe section 17. This will be disclosed by the fact that circulation of the "mud" is not possible because the 55 lower shoulder on the core barrel 36 has not passed through the lower end of the drill collar 17. In this case, it is necessary to raise the drill pipe a few feet bringing the drilling bit off the bottom of the hole and then lower it slowly while 60 rotating in a clockwise direction. This causes the collar 31 to change its position with relation to the bushing 22 and circulation is again attempted. This procedure is continued until the core drill and the core barrel have lowered sufficiently so 65 that the extensions or lugs 32 and 34 are in proper interlocking engagement with the bayonet joint at the lower end of the bushing 22.

When the core has been cut, the drill pipe is 70 raised a foot or so, with the core barrel, which causes the triangular members 54 to dig into the core, shearing it off, these members 54 dropping to a horizontal position and closing the bore of the core cutter head 29. The drill pipe is then again lowered to drilling position which removes 75

sembly from the rotary drill, and a core receiving barrel forming part of the assembly and disposed above the core cutting bit and having swiveled connection therewith.

5 2. In a core taking assembly for rotary drills, a core cutting bit, a core receiving barrel having swiveled engagement with the bit, the core barrel being longitudinally split to provide two half sections, said sections being complementarily recessed on the inner faces at their upper ends, a ball valve cage disposed within said sections and having a flange fitting said recesses, the cage having an internal upwardly opening ball valve and having a pull bar and spear head, and means for detachably holding the two sections of the core barrel in engagement with each other.

10 3. In a core taking assembly for rotary drills, a core cutting bit, a core receiving barrel disposed above the bit, a collar having screw-threaded engagement with the upper end of the core cutting bit and having swiveled engagement with the lower end of the core receiving barrel, and anti-friction bearings disposed between the upper end of the collar and an adjacent annular portion 15 of the core receiving barrel.

20 4. In a core taking assembly for rotary drills, a core cutting bit, a core receiving barrel disposed above the bit, a collar having screw-threaded engagement with the upper end of the core cutting bit and having swiveled engagement with the lower end of the core receiving barrel, and anti-friction bearings disposed between the upper end of the collar and an adjacent annular portion 25 of the core receiving barrel, the core receiving barrel on its outer surface adjacent its upper end having oppositely disposed ribs each extending spirally downward and around the barrel and the ribs extending in the same direction.

30 5. In a core taking assembly for rotary drills, a core receiving barrel formed in two longitudinal sections, and detachable split resilient rings embracing the two sections and holding the two sections of the barrel in engagement with each other to constitute a cylindrical barrel.

40 6. In combination with a tubular rotary drill, including an annular drilling bit, a core cutting bit disposed through the rotary drilling bit and projecting beyond the same, a core barrel swiveled to the upper end of the core cutting bit, the core cutting bit and the barrel being normally disposed within but being withdrawable from the main drilling bit, and coacting means on the main drilling bit and the core bit constructed and arranged to secure interlocking engagement between the core cutting bit and the rotary drilling bit upon rotation of the main drilling bit in one direction, said engagement being detachable upon a rotation of the main rotary drilling bit in the opposite direction to thus permit the bodily withdrawal of the core cutting bit and barrel.

50 7. A core taking assembly for rotary drills, the rotary drill including an annular main drilling bit, the assembly comprising a core cutting bit insertable through the main drilling bit, a core receiving barrel disposed above and operatively connected to the core cutting bit, and means constructed and arranged for detachably connecting the core cutting bit with the main drilling bit in only one predetermined position for unitary rotary movement in one direction but becoming disconnected therefrom upon a rotary movement of the main drilling bit in the other direction to thereby permit the lifting of the core taking assembly from the rotary drill by a wire line.

60 8. In combination, a tubular rotary drill

string, including an annular main rotary drill at the lower end of the string, a core cutting bit adapted to be disposed through the main drilling bit, a core receiving barrel operatively connected to the core cutting bit, coacting means on the confronting faces of the main drilling bit and the core cutting bit constructed and arranged to secure interlocking engagement between the core cutting bit and the main drilling bit upon a rotation of the main drilling bit in one direction, said engagement being detachable upon a rotation of the main drilling bit in the opposite direction to thereby permit the bodily lifting of the assembly through the rotary drill string, said means being constructed and arranged to prevent the interlocking of the core cutting bit with the main drilling bit except when the parts are in one predetermined position.

10 9. In combination, a tubular rotary drill string, including an annular main drill bit at the lower end of the string, a core cutting bit extending through the main drilling bit and having core catching devices on its inner face, a core barrel operatively swiveled to the upper end of the core cutting bit and having an upwardly opening valve at its upper end, the inner face of the main drilling bit being formed to provide opposed angular inwardly projecting lugs spaced from each other, the core cutting bit having complementary opposed angular lugs coacting with the first-named lugs to constitute a bayonet joint, one of said last-named lugs having a width greater than the other of said lugs and the space between the like ends of the first-named lugs being wider than the space between the opposite ends of the first-named lugs whereby to prevent interlocking engagement between the said lugs on the main drill and core drill except when the parts are in predetermined position.

20 10. In combination, a tubular rotary drill string, including an annular main drilling bit at its lower end, the drilling bit having ducts leading from the interior of the drilling bit downward and discharging between the blades of the drilling bit, the interior face of the main drilling bit below said ducts being screw-threaded, a bushing having threaded engagement with said last-named threads and extending downward on the inside of the main drilling bit, the bushing at its lower end having opposed angular lugs projecting inward and spaced from each other, the space between the lugs at one end being wider than the space between the lugs at the other end and a core taking assembly insertable through said drill string and the bit, comprising an annular core bit having means on its inside face whereby to cut and retain a core within the bit upon an upward movement of the bit, a collar having screw-threaded engagement with the upper end of the core cutting bit and having downwardly extending annular lugs constructed and arranged to have interlocking engagement with the lugs on the said bushing to form a bayonet joint connection, one of said lugs being narrower than the other lug whereby to prevent the interlocking of the lugs on the main drill bit with the lugs on said bushing except when the parts are in one predetermined relation, the core receiving barrel having swiveled engagement at its lower end with said second-named collar, and anti-friction bearings disposed between the barrel and its associated collar.

30 11. In an annular core drill, a core cutting and supporting means, comprising a plurality of cutters disposed equi-distantly around the inner

- face of the drill, each cutter being approximately triangular in facial elevation and the cutters together when lowered substantially closing the interior of the barrel and each cutter having its outer face formed with a longitudinally extending rib, the outer face on each side of said rib being transversely and longitudinally flat and having its inner face transversely curved to fit the curvature of the annular barrel, the apex of each cutter being curved inwardly and longitudinally and the drill having recesses in which the cutters are normally disposed with their inner faces flush with the inner face of the core drill, each cutter being pivoted at its lower end to the walls of the corresponding recess.
12. In an annular core drill, a core cutting and supporting means, comprising a plurality of cutters equi-distantly spaced around the inner face of the drill, each cutter being approximately triangular in facial elevation and having a transversely curved inner face fitting the curvature of the annular drill, the apex of each cutter being longitudinally and inwardly curved, the drill having recesses in which the cutters are normally disposed, the lower edge of each cutter having a downwardly extending lug formed with a vertical

opening, and a pivot pin passing through the opposed walls of each recess and through said opening.

13. In a core taking assembly for rotary drills, a core cutting bit, and a core receiving barrel above the bit and having swiveled engagement at its lower end with the bit, the bit and barrel being withdrawable as a unit.

14. In a core taking assembly for rotary drills, a core cutting bit and a core receiving barrel having swiveled engagement with the bit, anti-friction bearings disposed between the swiveled portions, the bit, the barrel and the anti-friction means being withdrawable as a unit from a rotary drill.

15. In a core taking assembly for rotary drills, a core cutting bit and a core receiving barrel having swiveled engagement with the bit, said barrel being longitudinally split throughout its entire length to form two halves, and split resilient rings engaging around the barrel at separated points for holding said halves in coaction with each other, the barrel being recessed to receive said rings.

ANCIL BROOKS CONKLIN.
